UNITED STATES PATENT OFFICE

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE

METAL STRUCTURE FOR RAILWAY CARS

Original application filed October 19, 1922, Serial No. 595,634. Patent No. 1,681,811, dated August 21, 1928. Divided and this application filed February 18, 1928. Serial No. 255,451.

My invention relates to the construction of railway cars, and more particularly to metal end structures or walls for railway cars made of one or more metallic plates or panels formed with integral reinforcing, stiffening and bracing embossments or corrugations. However, this device may be incorporated in the construction of car side walls, floors, roofs or doors used in connection with railway cars 10 of various types.

It is well known that the end walls of railway cars are more likely to be broken or otherwise injured than the side walls. This is due to the inertia thrusts and pressures 15 caused by the shifting of the cargoes when the train starts or stops. These thrusts may be local, tending to distort the end in some particular spot, as, for example, when a piece of piping or lumber shifts lengthwise imparting a blow against the end wall of the car; or there may be a general tendency to break out the end wall as a whole or tear it away 20 from the framing. For the purpose, therefore, of greater strength and durability, car 25 ends have been constructed of metal plates corrugated or formed with ribs to impart the desired strength, rigidity and resiliency.

One of the principal objects of my invention is to provide a corrugated or embossed 30 metallic end structure for railway cars in which the corrugations or embossments have a configuration and arrangement that impart to the structure a maximum capacity for resisting cargo thrusts, both local and general, 35 static or quiescent, and with sufficient resiliency to prevent permanent distortion due to the thrusts of the loads, with a minimum weight of metal. It is important that structures of this sort should be as light as is 40 possible, consistent with strength and durability, both for reasons of economy in manufacturing cost and also to keep the weight of the car at a minimum.

A further object is to provide a corrugated 45 metallic wall element that is practically pos-

sible to manufacture. A further object is to provide a metallic wall element with corrugations or embossments that resist to a greater degree torsional stresses, as well as brace the element, and the car end against 50 diagonal side thrusts or weaving.

Another object is to form a metallic plate with integral corrugations or embossments which impart to it a certain amount of strength and rigidity to resist loads imposed 55 thereon and to so form the ends of the corrugations or embossments as to provide a certain amount of resiliency to enable the plate to deflect and return to its normal position without appreciable amount of permanent 60 distortion.

In the drawings:

Fig. 1 is an end elevation of a car equipped with my invention.

Fig. 2 is a section on line 2—2 of Fig. 1.

Fig. 3 is a front view of a corrugated plate.

Fig. 4 is a top view of Fig. 3.

Fig. 5 is a section on line 5—5 of Fig. 3.

Fig. 6 is a section on line 6—6 of Fig. 3.

Fig. 7 is a section on line 7—7 of Fig. 3. 70

Fig. 8 is an enlarged section of a portion of the plate on line 5—5 of Fig. 3.

Fig. 9 is an enlarged section of a portion of the plate on line 6—6 of Fig. 3.

Fig. 10 is an enlarged section of a portion of the plate on line 7—7 of Fig. 3. 75

Like characters of reference designate like parts.

Referring to Figs. 1 and 2, the corrugated or embossed plates or panels 1, 2 and 80 3 extend across the car from side to side and are formed with integral flanges 4 along the vertical edges which overlap and are secured to the frame members of the side walls 5 of the car by any suitable means. The top edge 85 of the end wall is secured beneath the fascia boards 7 and the meeting edges of the plate overlap and are secured together by rows of rivets 8 and the lower edge of the end wall is secured to the end sill 9. Nailing strips 90

10 are secured to the plates 1, 2 and 3 by bolts and lining 11 is secured to the nailing strips 10.

15 While the corrugations or embossments are shown pressed outwardly from the original plane of the plate and in horizontal arrangement, it is understood that the corrugations or embossments may be pressed inwardly or partially inwardly and partially outwardly from the original plane of the plate, or the corrugations or embossments may be placed in any position; for instance, vertically or horizontally. The plates or panels may be applied to any type of railway car.

20 Figs. 3 to 10 inclusive show the preferred form wherein the plate is provided with a plurality of major corrugations or embossments 20 with arcuate apices which are spaced apart distances substantially equal to their respective widths and the parts 21 of the plate between the major corrugations or embossments are also arcuate so that the configuration is symmetrical in cross section about a line midway between the outermost portions 25 of these major corrugations or embossments (see Fig. 5) which line is the neutral axis of the section. Such a section is very strong on account of the amount of metal positioned away from the neutral axis and is also relatively rigid. The arcuate apices of the major corrugations or embossments 20 and the arcuate part 21 of the plate function as arches to transmit any load imposed thereon to the opposite walls 26-27 of the major corrugations or embossments. These major corrugations or embossments 20 are preferably widest and deepest adjacent their middle portion and decrease in width toward their opposite ends and the radii of the arcuate apices 30 decreases toward the ends of the embossments. The metallic plate is also provided with a plurality of aligned minor corrugations or embossments 24 which lie between adjacent major corrugations or embossments 40 with their inner end terminating into the plate (25) and with their outer ends terminating into the plate in line with the outer ends of the major corrugations or embossments.

45 The outer ends of the minor corrugations or embossments 24 have arcuate apices and the parts 25 of the plate between the outer ends of the minor corrugations or embossments and the outer ends of the major corrugations or embossments are also arcuate so that they form a cross section of sinuous configuration, and, furthermore, the outer ends 50 of the major and minor corrugations or embossments are equal in width and spaced apart distances substantially equal to their respective widths so that they form a contiguous sinuous configuration symmetrical in cross section about a line midway between the outermost portions of the corrugations or embossments (see Fig. 7) which line is the

neutral axis of the section. Such a section is very resilient and has a spring like action under load, and, further, produces a very strong section for the amount of metal used. The major and minor corrugations or embossments merge into the plane of the plate by means of terminal portions 26 of any desired formation. By such an arrangement a corrugated metallic plate is provided which is relatively rigid adjacent the middle of the plate and relatively resilient adjacent the opposite end portions of the corrugations or embossments.

55 I have designed my invention for use in steel plates so that when the section modulus of any section (normal to the corrugations) is multiplied by a constant fibre stress the result equals the bending moment of that section for either a load concentrated at the middle of the corrugated part of the plate or for a load equally distributed over the corrugated part of the plate, thus showing that I have not sacrificed any required strength at the ends of the beams to obtain resiliency; in other words, by my construction I obtain a 60 very strong plate which is also resilient.

50 As the major corrugations increase in width and depth toward their middle portion, the minor corrugations decrease in width and depth proportionately so that the lengths of 65 the center lines of the metal of all cross sections of the corrugated portion of the plate are equal.

60 The major and minor corrugations may be positioned and dimensioned so that the length 70 of the center lines of the metal of a cross section of the major corrugations adjacent their middle (see Fig. 5) is the same as the length of the center line of the metal of a cross section of the major and minor corrugations adjacent their end portions. (See Fig. 7.) Furthermore, the corrugated plate may be 75 so formed that the length of the center line of the metal of any cross section (for instance, as per Fig. 6) is equal to the length of the 80 center line of the metal of any other cross section, that is, between the terminal portions. This is a material manufacturing advantage as it more evenly distributes the 85 draw and stretch of the metal due to pressing 90 the corrugations in the plate.

95 Plates provided with a plurality of contiguous narrow corrugations or embossments possess a considerable amount of elasticity and when struck a blow deflect readily and 100 regain their shape without distortion, whereas, a plate provided with wide arcuate corrugations, though better able to carry quiescent loads, has not the resiliency of the former and is more readily distorted when 105 struck a blow.

110 It is, therefore, desirable to design a plate 115 that possesses great strength to withstand the sudden impact loads or blows with sufficient resiliency to resist distortion.

The major corrugations or embossments 20 are of uniform width for a short distance at the center of the plate, the object being to form a corrugated plate of greater strength for a wider portion of the plate and also to facilitate the changing of the dies used for forming the corrugations or embossments.

The drawings illustrate the preferred form of the invention, though it is to be understood that the invention is not limited to the exact details of construction shown and described, as it is obvious that various modifications thereof within the scope of the claims will occur to persons skilled in the art.

This is a division of application No. 595,634, filed October 19, 1922, which matured into Patent No. 1,681,811 on August 21, 1928.

I claim:

1. A metallic plate formed with a plurality of major embossments with arcuate apices, said plate also provided with pairs of aligned sinuous minor embossments lying between said major embossments.

2. A metallic plate formed with a plurality of major embossments with arcuate apices decreasing in width toward their ends, said plate also provided with pairs of aligned sinuous minor embossments lying between said major embossments which increase in width toward their outer end and terminate into the plate substantially in alignment with the major embossments.

3. A metallic plate formed with a plurality of major embossments with arcuate apices decreasing in width and in depth toward their ends, said plate also provided with pairs of aligned sinuous minor embossments lying between said major embossments which increase in width and in depth toward their outer ends and terminate into the plate substantially in alignment with the major embossments.

4. A metallic plate formed with a plurality of major embossments with arcuate apices with the parts of the plate between the major embossments also of arcuate configuration, said plate also provided with pairs of aligned sinuous minor embossments lying between said major embossments with the parts of the plate between the adjacent ends of the major and minor embossments also of sinuous configuration.

5. A metallic plate formed with a plurality of major embossments with arcuate apices with the parts of the plate between the major embossments also of arcuate configuration, said embossments decreasing in width toward their ends, said plate also provided with pairs of aligned sinuous minor embossments lying between said major embossments with the parts of the plate between the adjacent ends of the major and minor embossments also of sinuous configuration.

6. A metallic plate formed with a plu-

rality of major embossments with arcuate apices with the parts of the plate between the major embossments also of arcuate configuration, said embossments decreasing in width and in depth toward their ends, said plate also provided with pairs of aligned sinuous minor embossments lying between said major embossments with the parts of the plate between the adjacent ends of the major and minor embossments also of sinuous configuration.

7. A metallic plate formed with a plurality of major embossments with arcuate apices spaced apart distances substantially equal to their width with the parts of the plate between the major embossments also of arcuate configuration, said plate also provided with pairs of aligned sinuous minor embossments lying between said major embossments, the outer ends of the major and minor embossments being spaced apart distances substantially equal to their width with the parts of the plate between the adjacent ends of the major and minor embossments also of sinuous configuration.

8. A metallic plate formed with a plurality of major embossments with arcuate apices spaced apart distances substantially equal to their width with the parts of the plate between the major embossments also of arcuate configuration, said embossments decreasing in width toward their ends, said plate also provided with pairs of aligned sinuous minor embossments lying between said major embossments, the outer ends of the major and minor embossments being spaced apart distances substantially equal to their width with the parts of the plate between the adjacent ends of the major and minor embossments also of sinuous configuration.

9. A metallic plate formed with a plurality of major embossments with arcuate apices spaced apart distances substantially equal to their width with the parts of the plate between the major embossments also of arcuate configuration, said embossments decreasing in width and in depth toward their ends, said plate also provided with pairs of aligned sinuous minor embossments lying between said major embossments the outer ends of the major and minor embossments being spaced apart distances substantially equal to their width with the parts of the plate between the adjacent ends of the major and minor embossments also of sinuous configuration.

10. A metallic plate formed with a plurality of major embossments with arcuate apices with the parts of the plate between the major embossments also of arcuate configuration, said embossments and said parts forming a cross section symmetrical about a line midway between their outermost portions, said plate also provided with pairs of aligned sinuous minor embossments lying between

said major embossments with the parts of the plate between the adjacent ends of the major and minor embossments also of sinuous configuration, the adjacent ends of the major and minor embossments forming a cross section symmetrical about a line midway between their outermost portions.

11. A metallic plate formed with a plurality of major embossments with arcuate apices with the parts of the plate between the major embossments also of arcuate configuration, said embossments and said parts forming a cross section symmetrical about a line midway between their outermost portions, said embossments decreasing in width toward their ends, said plate also provided with pairs of aligned sinuous minor embossments lying between said major embossments with the parts of the plate between the adjacent ends of the major and minor embossments also of sinuous configuration, the adjacent ends of the major and minor embossments forming a cross section symmetrical about a line midway between their outermost portions.

12. A metallic plate formed with a plurality of major embossments with arcuate apices with the parts of the plate between the major embossments also of arcuate configuration, said embossments and said parts forming a cross section symmetrical about a line midway between their outermost portions, said embossments decreasing in width and in depth toward their ends, said plate also provided with pairs of aligned sinuous minor embossments lying between said major embossments with the parts of the plate between the adjacent ends of the major and minor embossments also of sinuous configuration, the adjacent ends of the major and minor embossments forming a cross section symmetrical about a line midway between their outermost portions.

13. A metallic plate formed with a plurality of major embossments with arcuate apices spaced apart distances substantially equal to their width having their opposite ends terminating into the plate with the parts of the plate between the major embossments also of arcuate configuration, said embossments and said parts forming a cross section symmetrical about a line midway between their outermost portions, said embossments decreasing in width and in depth toward their ends, said plate also provided with a plurality of sinuous minor embossments lying between said major embossments which increase in width and in depth toward their outer ends until the major and minor embossments are spaced apart distances substantially equal to their width with the parts of the plate between the adjacent ends of the major and minor embossments also of sinuous configuration, the adjacent ends of the major and minor embossments forming a

cross section symmetrical about a line midway between their outermost portions.

14. A wall for a railway car comprising a metallic plate secured to oppositely disposed frame members of the car, said plate provided with a plurality of major embossments with arcuate apices with the parts of the plate between the major embossments also of arcuate configuration, said plate also provided with a plurality of sinuous minor embossments lying between said major embossments with the parts of the plate between the adjacent ends of the major and minor embossments also of sinuous configuration, the outer ends of the major and minor embossments terminating into the plate adjacent said oppositely disposed frame members.

15. A wall for a railway car comprising a metallic plate secured to oppositely disposed frame members of the car, said plate provided with a plurality of major embossments with arcuate apices with the parts of the plate between the major embossments also of arcuate configuration, said plate also provided with a plurality of sinuous minor embossments lying between said major embossments with the parts of the plate between the adjacent ends of the major and minor embossments also of sinuous configuration, the outer ends of the major and minor embossments being substantially in alignment and terminating into the plate adjacent said oppositely disposed frame members.

16. A metallic structure for a railway car, comprising a metallic plate secured to oppositely disposed frame members of the structure, said plate provided with a plurality of varying depth major corrugations with arcuate apices with the parts of the plate between the major corrugations also being arcuate, said plate also provided with a plurality of minor corrugations lying substantially between the major corrugations which terminate into the plate adjacent said frame members substantially in alignment with said major corrugations where the said major and minor corrugations have arcuate apices and the parts of the plate between the ends of the major and minor corrugations are also of arcuate configuration.

17. A metallic plate provided with a plurality of major embossments having arcuate apices with the parts of the plate between the embossments also of arcuate configuration, said major embossments decreasing in width and in depth toward their opposite ends, said plate also provided with a plurality of minor embossments lying substantially between the major embossments which increase in width and in depth toward their outer ends and terminate into the plate substantially in alignment with the major embossments where the major and minor embossments have arcuate apices and the parts of the plate between the ends of the major and minor embossments forming a

bossmets are also of arcuate configuration.

18. A metallic plate provided with a plurality of major embossments having arcuate apices, said plate also provided with a plurality of minor embossments lying substantially between the major embossments which terminate into the plate substantially in alignment with the major embossments where the major and minor embossments have arcuate apices and the parts of the plate between the ends of the major and minor embossments are also of arcuate configuration.

19. A structure for a railway car comprising a metallic plate secured to oppositely disposed frame members of the car, said plate provided with a plurality of major embossments having arcuate apices with the parts of the plate between the embossments also of arcuate configuration, said plate also provided 20 with a plurality of minor embossments lying substantially between the major embossments which terminate into the plate adjacent said oppositely disposed frame members where the major and minor embossments have arcuate apices and the parts of the plate between the ends of the major and minor embossments are also of arcuate configuration.

20. A structure for a railway car comprising a metallic plate secured to oppositely disposed frame members of the car, said plate provided with a plurality of major embossments having arcuate apices with the parts of the plate between the embossments also of arcuate configuration, said major embossments decreasing in width toward their opposite ends, said plate also provided with a plurality of minor embossments lying substantially between the major embossments which increase in width and terminate into 35 the plate adjacent said oppositely disposed frame members where the major and minor embossments have arcuate apices and the parts of the plate between the ends of the major and minor embossments are also of arcuate configuration.

21. A structure for a railway car comprising a metallic plate secured to oppositely disposed frame members of the car, said plate provided with a plurality of major embossments having arcuate apices with the parts of the plate between the embossments also of arcuate configuration, said major embossments decreasing in width and in depth toward their opposite edges, said plate also provided with a plurality of minor embossments lying substantially between the major embossments which increase in width and in depth toward their outer ends and terminate into the plate adjacent said oppositely disposed frame members where the major and minor embossments have arcuate apices and the parts of the plate between the ends of the major and minor embossments are also of arcuate configuration.

22. A structure for a railway car comprising

ing a metallic plate secured to oppositely disposed frame members of the car, said plate provided with a plurality of major embossments having arcuate apices, said plate also provided with a plurality of minor embossments lying substantially between the major embossments which terminate into the plate adjacent said oppositely disposed frame members where the major and minor embossments have arcuate apices and the parts of the plate between the ends of the major and minor embossments are also of arcuate configuration.
